UNITED STATES PATENT OFFICE.

FRED D. SHERWIN, OF EDGAR, NEBRASKA.

DENTAL SALIVA-EJECTOR.

SPECIFICATION forming part of Letters Patent No. 530,556, dated December 11, 1894.

Application filed March 28, 1894. Serial No. 505,461. (No model.)

To all whom it may concern:

Be it known that I, FRED D. SHERWIN, a citizen of the United States, residing at Edgar, in the county of Clay and State of Nebraska, have invented a new and useful Saliva-Ejector for Dentists, of which the following is a specification.

My invention relates to an improvement in those saliva removers wherein the saliva is drawn from the patient's mouth by way of a tube, and the tube made to empty into a chamber, the chamber being connected to the pipe for creating the air-pressure necessary to the drawing of the saliva; and it consists principally of an improvement in the construction of the chamber for joining the two tubes, whereby the operation of the device is rendered more effective and the saliva prevented from entering the suction or exhaust tube.

In the accompanying drawings: Figure 1 represents a perspective view of my improvement in position for use; Fig. 2, an enlarged section of the device; Fig. 3, a view of the valve for closing the suction chamber.

The reference numeral 1 indicates the saliva-removing tube, which may be of any suitable length and which is provided at its outer end with the mouth-piece 2. This device is curved or bent to assume a form approximately semicircular, and is provided with the enlarged end or bulb 3, which is perforated, as shown, so that the saliva may be drawn into the tube. By means of the curved shape of the mouth-piece 2 it may be placed in the patient's mouth and will remain in position by hanging over his lower lip. From the mouth-piece 2 the tube 1 extends down to the suction chamber 4, to which it is connected by means of the metallic tube 5 of the suction chamber. The latter device is formed, preferably, of sheet-metal and shaped as an inverted cone, having at its upper side, or at the base of the inverted cone, the said tube 5, which projects a slight distance above the upper side and is connected, by any suitable means, to the tube 1, as before stated. Below the upper side of the chamber 4 the tube 5 extends down, centrally, to a point directly adjacent to the lower extremity of the chamber, or the apex of the cone, and the said

apex is extended or provided with the nozzle 6, into which the tube 5 empties.

Secured to the lower end of the nozzle 6, and extending outwardly and horizontally therefrom, is the flat arm 7. This arm is 55 formed of a strip of sheet-metal, preferably copper, and arranged horizontally, and the outer end of the arm is bent downwardly and thence back parallel with the main portion, and has arranged between it and said main 60 portion the flexible rubber valve-plate 8. Valve-plate 8 extends beyond the end of the arm and inwardly toward the nozzle 6, under which it is arranged and adapted to close. Thus it will be seen that air-pressure into 65 the nozzle 6 will cause the valve to close the opening, and when pressure is exerted in the opposite direction the valve will be opened.

9 indicates the air-pressure or suction tube, by which the pressure of air in the chamber 4 is regulated, and this is connected to chamber 4 by means of the short tube 10, which is arranged near the periphery of the upper side of the chamber, and communicates with the interior thereof. The upper end of the tube 70 10 is bent out at right angles to the main portion, and it is to this bent section that the tube 9 is connected, whereby the tube is given a normal tendency to extend horizontally. From the tube 10 the rubber tube 9 extends 75 80 away, and is connected to the bulb 11. This bulb is provided with the valves 12 and 13, the valve 12 being directly adjacent to the end of the tube 9 and opening away from it, while the valve 13 is at the opposite end of 85 the bulb and opens similarly. Thus, by compressing the bulb the air will be excluded therefrom, and as the bulb regains its shape the air is drawn through tube 9, which exhausts chamber 4, since the valve-plate 8 will 90 operate to close the nozzle 6. The exhausting of the air in chamber 4 will be followed by a consequent pressure in the tube 1, and an operation of the mouth-piece 2 to draw inwardly. This will draw the saliva into the 95 tube 1 and thence through the tube 5, and into the nozzle 6, where it will remain until its weight causes the plate 8 to swing down and thereby release it. Owing to the arrangement of the tubes 5 and 10, and their 100

comparative location, it will be impossible for the saliva to enter the tube 9, since it will pass out the nozzle 6 before it will be forced to move up the chamber to the tube 10.

- 5 It is essential to the operation of the device that the plate 8 be very sensitive, and capable of withstanding the weight of but little saliva, so that the danger of the saliva entering the tube 9 is greatly lessened. It is also 10 essential that this valve-plate be capable of effectively closing the nozzle, for without this the tube 9 would draw through the nozzle 6, and thus defeat the successful operation of the device. Secured to the periphery of the 15 upper side of the chamber 4, is the hook 14, which is formed preferably of wire and bent outwardly and thence downwardly, so as to be capable of taking over the edge of an edged object, and thereby supporting the chamber 4. 20 To use my invention, the hook 14 is made to engage the edge of a cuspidor or other suitable receptacle, as shown in Fig. 1, so that the nozzle 6 will point down into the body of the receptacle, and the upper face of the 25 chamber 4 lie flush with the edge thereof. The mouth-piece 2 is then placed in the patient's mouth and the bulb 11 operated to exhaust the air in the chamber 4, which operation will be followed by the drawing of the 30 saliva from the patient's mouth, and into the chamber 4, from which it falls, by the operation of the plate 8, as before described. Should it be desired to operate the bulb by foot-pressure, the bulb may be placed on the floor, 35 and compressed by foot-power; and if necessary, a suitable seat may be provided for it, whereby the bulb is held stationary. This, however, is well understood by all skilled in the art and does not require any detail 40 description. It is also understood by those acquainted with such matters that the bulb 11 may be replaced by any other device capable of creating a vacuum, or partial vacuum, in the several tubes of my invention, such as an 45 air pump, blower or other arrangement, all

of which are in common use and do not require illustration in the drawings, or further mention in the specification.

I desire it understood that I am not limited to the use of a conical chamber 4, but that 50 any form may be used as well. Indeed, the chamber could be changed to assume the shape of an oval, with advantages as many as, if not more than, those attending the conical form. 55

Having described my invention, what I claim is—

1. A device for removing saliva, and comprising in its construction a chamber adapted to receive the saliva and to form a connection between the saliva-conveying and air-exhausting pipes, the lower end of said chamber being provided with a nozzle, a plate connected to the nozzle and extending laterally therefrom, the end of said plate being bent 65 to form a clasp, and a rubber valve-plate held by said clasp and arranged over the mouth of the nozzle, substantially as described.

2. A device for removing saliva, and consisting of a tube adapted to be placed in the patient's mouth, a chamber having the said tube entering at its upper end and extending down to the lower end of the chamber, at which portion it discharges its contents, an outwardly-opening valve at the lower portion 75 of the chamber, and through which the saliva from the said tube passes from the chamber, a second tube communicating with the upper side of the chamber, and an air-exhausting apparatus connected to the second tube, and 80 whereby the first tube is made to draw the saliva and discharge it upon the valve, substantially as described.

In testimony that I claim the foregoing as my own I have hereto affixed my signature in 85 the presence of two witnesses.

FRED D. SHERWIN.
